CLAIM

The ornamental design for a phone case, as shown and described.

DESCRIPTION

FIG. 1 is a front perspective view of a phone case showing my new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 9 is a front perspective view of one open configuration of the phone case thereof;

FIG. 10 is a front perspective view of a second open configuration of the phone case thereof;

FIG. 11 is a top, front perspective view of an example use configuration of the phone case thereof;

FIG. 12 is a top, back perspective view of an example use configuration of the phone case thereof;

FIG. 13 is a second front perspective view of the phone case shown with an environmental wrist loop; and,

FIG. 14 is a second front view shown with an environmental shoulder strap.

The broken lines shown in the drawings depicting portions of the phone case form no part of the claimed design; the broken lines shown in the drawings depicting stitching on the surfaces of the phone case form a part of the claimed design; and the broken line wrist loop and shoulder strap appearing in FIGS. 13 and 14 represent environmental subject matter included for the purpose of demonstrating potential use states for the phone case.

1 Claim, 14 Drawing Sheets
